A technical diagram of a curved metal component, likely a bracket or part of a hinge mechanism. The component is U-shaped and curved. Several parts are labeled with numbers: 31 is a vertical tab on the left; 30 is a slot or opening at the top; 33 is a slot on the right; 37 is a slot on the bottom left; 36 is a slot on the bottom right; and 32 is a slot on the far left. The word "Will" is written in cursive across the bottom right of the diagram.

33 Inventor:
William F. Cremeán,
By Parker Att'y.

UNITED STATES PATENT OFFICE

WILLIAM F. CREMEAN, OF TOLEDO, OHIO

DUST GUARD

Application filed January 21, 1930. Serial No. 422,370.

My invention relates to new and useful improvements in dust guards for the journal boxes of railway cars and has for an object to provide a dust guard that will fit closely around the dust guard bearing of the axle to exclude the dust and prevent the escape of oil and waste.

The present application is a companion case to the one filed by me on March 11, 1929 and bearing Serial Number 346,165.

One of the objects of the present invention is to provide a dust guard that will be extremely light in weight and efficient in service.

Still another object of the invention is to provide a dust guard comprising a metal holder or frame, in which there is placed a ring, which, in turn, is formed with a pliable material, such as lamp wicking or cotton webbing, securely held in a metal backing.

Still another object of the invention is to provide a dust guard formed of relatively thin sheet metal, in which there is a wick crimped in a metal backing, which wick with its metal backing may easily be removed from the plate and a new one inserted when necessary.

Still another object of the invention is to provide a dust guard comprising a plate in which there fits the removable metal-backed wick, the said metal-backed wick being broken at its upper portion and the ends abutting, which ends are locked in place by a metal block of special design and configuration.

In the companion case, the metal-backed wick had the ends fitting in the ends of a block, which block, in turn, was fitted up within the metal holder, whereas in the present instance, the ends of the metal-backed wick abut or nearly abut and are tightly locked in place by a special form of metal block, hereinafter to be more fully described.

Still another object of the invention is to provide a dust guard that is extremely cheap to manufacture and wherein the ring wick may be easily renewed and the metal plate itself be used indefinitely.

With these and other objects in view, the invention consists in certain new and novel

arrangements and combination of parts, as will be hereinafter more fully described and pointed out in the claims.

Referring now to the drawings showing a preferred embodiment,

Fig. 1 is a plan view of my improved dust guard showing the wick ring in position;

Fig. 2 is a sectional view taken on the line 2-2 and looking in the direction of the arrows, but with the wick removed;

Fig. 3 is a sectional view taken on the line 3-3 of Fig. 1 on an enlarged scale;

Fig. 4 is a sectional view taken on the line 4-4 of Fig. 1;

Fig. 5 is a sectional view taken on the line 5-5 of Fig. 1;

Fig. 6 is a sectional view taken on the line 6-6 of Fig. 1;

Fig. 7 is a fragmentary detail of the rear of the block and showing the several adjacent and associated parts;

Fig. 8 is a perspective of the block.

Referring now to the several views and Fig. 1 in particular, it will be seen that my improved dust guard consists of a sheet metal plate 1 having the outstanding flanges 2 along the sides. The bottom of the plate is rounded, as at 3, while the top 4 is flat across its entire width. The top of the plate is provided with the offset flange 5, while its edge 6 is slightly curled, as may be seen in Figs. 1 and 2.

It will also be seen that there is the small flange 7 at the bottom with the slightly curled edge 8, thus the edge 8 and the top 6 of the flange 5 being in the same vertical plane, so that when the dust guard is placed in the dust box (not shown), it will bear against the opposite walls of the same from the main plate 1.

As far as the specification has proceeded, it will be understood that it is the same as the companion case, with the exception that the flange 7 in the present instance extends rearwardly substantially in one plane and the flange 8 is slightly less rounded.

The central portion of the plate 1 is cut out, as at 9, the opening being slightly larger than the circumference of the car axle (not shown).

About the wall of the circular opening 9, there will be seen the depressed rib 10, which extends entirely around the same and this is depressed in the opposite direction from that shown in the companion case.

5 There is a slight circular space 13 which, in reality, forms a rim between the rib 10 and the edge of the peripheral wall of the opening 9, which is partly cut out to form lips in 10 staggered relation, as may be seen in Fig. 1 and the other several views.

15 Referring for the moment to Fig. 5 which is a section on the line 5-5 of Fig. 1, it will be seen that the peripheral edge 14 at this point is in the normal plane of the plate. However, the metal is then split or cut, as at 15 and 16, to form the lug or lip 17, as may be seen in Fig. 6, that is, this metal is pressed inwardly, as viewed from Fig. 1 or, in other 20 words, is offset from the part 14 to form a retaining lip.

25 There are a number of these lips formed in the same way, such as 18, 19, 20 and 21, the metal left in the original plane also forming retaining lips, alternately thereof.

30 These lips are similar to the ones shown in the companion case, but in the present instance they are pressed inwardly, as viewed from Fig. 1 rather than outwardly as they are in the companion case.

35 Now at the top of the circular opening, the metal is cut and offset to form two lips 22 and 23, while the central section 24 between these two lips is offset slightly in the opposite direction, as may be seen at 25, (See Fig. 4); the purpose of these three lips being to receive and hold a small locking and bearing block 26 which is to be made of a relatively soft metal, such as lead or babbitt or any 40 other similar metal, and is of special design and configuration to tightly lock within the offset lips or lugs just mentioned a split metal ring 28 in which there is crimped the wick 29, which wick is adapted to tightly fit or 45 hug the car axle (not shown).

50 Now rather than having the ends of the crimped metal rings set within the block, as shown in the companion case, in the present instance I have the two ends of the ring abutting or substantially abutting directly in the center of the plate and, therefore, beneath the pressed-back lug or lip 24. The remainder of the crimped metal ring, of course, fits under the previously mentioned lips 17, 18, 55 19, etc. and between the normal portions of the rim that are not pressed back, so that the ring will be tightly held in position after once being inserted.

60 Referring more particularly to the gist of the invention and to the manner of holding these abutting ends of the crimped metal ring in place, reference is made to the bearing block 26. As may be seen in Fig. 8, this block 26 comprises the body portion 30 with the 65 upstanding lug 31 and the reduced end portions

32 and 33 which are to be forced behind the portions of the rim, as may be seen in Fig. 2.

By forming the block in this manner, it will be seen that after the same is wedged up into place behind the two lugs 22 and 23 on the face of the plate and up behind the lug 24 to the rear of the plate, and by providing the little top lug 31 to also jam against the face of the plate, the little block will be snugly held in the plate and, in turn, will snugly hold the ends of the metal-backed wick in position.

It will also be seen that this block 26 has the downwardly projecting portion 36, which is arcuate, so that this portion may 80 bear directly on the axle (not shown) and help hold the plate in position.

85 On the rear face of the block, there is shown (Figs. 4 and 8) an overhanging lip 37, so that the ends of the metal wick when in position will be held against any springing or upward movement, as this lip 37 overhangs the two edges, as just explained. The overhanging lip is also arcuate in plan.

90 In other words, the rear face of the block projects outwardly and the projection following an arc similar to the arc of the metal-backed ring.

95 Now to put in a new ring, it is a very simple matter to knock the block downwardly out of position, slip in a new ring and wedge a new block up in place.

100 From the foregoing, it will be seen that I have produced a metal dust guard that is extremely cheap to manufacture wherein a new wick may be quickly locked in position.

105 The ends of the metal-backed ring will be brought right together at the top of the plate, after which the soft metal block will be jammed up behind the two lips on the one side and in front of the lug on the rear side, while the little projecting ends will extend slightly beyond the two adjacent portions of the rim, as illustrated, to thus tightly lock the metal-backed wick in place.

110 Having thus described my invention, what I claim as new and desire to secure by Letters Patent is:—

115 1. A dust guard comprising a metal plate having a large central opening, the walls about the opening cut to form staggered lips, a removable metal-bound wick fitted within said staggered lips, additional lips at the top of the opening, the ends of the metal-bound wick directly opposite one of the additional lips, a metal block jammed over the said ends and between the said additional lips at the top of the opening to thereby lock the metal-bound wick in position.

120 125 2. A dust guard comprising a metal sheet, said metal sheet being flat across the top and rounded at its bottom, said plate provided with a large central opening, the walls about said opening being pressed to form retaining lips and adapted to hold a composite split 130

ring axle bearing member, two additional lips at the top of the opening on the one side of the plate and spaced apart and a further lip on the other side of the plate opposite the space between the two aforementioned lips, the ends of the split ring lying in front of the last-mentioned lip, a block with an upstanding lug and reduced end portions jammed up between the three said lips and interlocking between said lips to thereby jam the ends of the ring tightly between the said lips and blocks.

3. A dust guard formed of a metal sheet together with a fixedly held split metal ring, said metal ring having an axle-engaging means associated therewith, integral means about the opening for holding the ring in position, a metal plug having an upstanding lug and end portions fitting up within the means for holding the ring in position, said plug having an overlying ledge whereby the ends of said ring are tightly clamped in position and also prevented by said ledge from springing upwardly.

4. A dust guard comprising a metal plate provided with a large central opening, staggered lips around the edge of the opening, a metal-bound wick in the form of a split ring held within said lips, additional lips at the top of the opening, one on one side of the plate and two on the opposite side of the plate to thereby receive the ends of the ring, a metal block with an upstanding lug and outwardly projecting reduced ends also projecting between said last-mentioned lips to tightly hold the ends of the ring between said lips.

5. A dust guard comprising a metal plate with a large central opening, a wick in the form of a split ring with a metal-bound back fitted about the walls of the opening, lips disposed on the opposite side of the plate at the top of the opening for contacting with the ends of the wick, a metal plug having an upwardly extending lug, outwardly extending end portions and an arcuate overlying ledge jammed between said lips and over the ends of the ring to tightly hold the same in position and to provide against any upward movement of its ends.

6. A dust guard comprising a metal plate with a central opening and the walls about the opening cut to form lips, a metal-bound wick in the form of a split ring fitted within the lips and having their ends abutting, a lip behind the abutting edges and lips just beyond the abutting edges formed in the plate, a metal block fitted within said lips and overlapping the ends, and the said metal block having an overlying arcuate ledge to thereby hold the ends of the wick against movement.

7. A metal dust guard having a large central opening and means about the opening for holding an axle-bearing member, said

axle-bearing member being in the form of a split ring, the said ends of the ring fitting within certain of said lips and their ends abutting each other, a metal wedge formed to interlock within said lips and to overlap the abutting edges of the ring, the said wedge having a downwardly projecting portion adapted to rest on an axle and an overlying edge formed on said wedge to thereby prevent the ends of the split ring from springing upwardly.

8. A plug for holding the ends of a split ring within a dust guard, said plug comprising a body portion and an upstanding lug, the opposite sides of the body portion having reduced ends, a depending portion adapted to rest on a car axle and one face of the plate being provided with an overhanging ledge and extending arcuately across the body portion.

9. A block for holding the ends of a split ring tightly within a dust guard, said block comprising a body portion with an upwardly extending central lug, the sides of the body portion being slightly reduced, and an arcuate overhanging ledge formed on one face of the body portion.

In testimony whereof I affix my signature.

WILLIAM F. CREMEAN.
